WOOD CELLULAR LAMINATED RAILWAY CAR

Bertrand Goldberg, Chicago, Ill., assignor to
 Pressed Steel Car Company, Inc., Chicago, Ill.,
 a corporation of Pennsylvania

Application April 27, 1951, Serial No. 223,248

30 Claims. (Cl. 105—404)

1

This invention relates to railway car construction and involves improved structural features in the construction of a railway car made from wood, laminated plywood and veneers, the several parts being adhesively joined together.

The fundamental object of the instant invention is to provide improved formation and arrangement of parts and elements over the structure shown in my copending application Serial No. 151,883, filed March 25, 1950.

A specific object of the invention is to provide improved end and side wall construction in plywood freight cars yet retain the virtues of the monocoque cellular construction.

It is a further object of the invention to provide an improved floor construction characterized by longitudinal and transverse arrangements of joints thereunder.

It is a further object of the invention to provide an improved plywood cellular freight car construction wherein the yoke and bolster construction provide for improved load distribution and shock absorption in the car.

Other objects both specific and general will in part be obvious and in part appear herein-after.

This invention accordingly is embodied in a freight car construction characterized by being of a cellular or monocoque formation employing plywood largely in the formation thereof, the invention including the features of construction, combinations of elements and arrangements of parts hereinafter to be described in greater detail.

It should be understood that the fundamental features of the construction are useful in forming cars for carrying ordinary freight or for use in refrigerator cars. Where a car is to be used as a refrigerator unit, the certain additional features provided to permit cooling of goods stored therein are peculiar to the formation of refrigeration units themselves rather than to the car construction.

In the drawings, Figure 1 is a side elevation of the car partly in the section showing the general arrangement of parts and illustrating the manner in which the cellular construction is carried through the walls, roof and end of the car.

Figure 2 is a plan view of the car showing it partially in section so that the cellular construction of the roof and the framing of the floor and the relation thereof to the bolster and yoke may be determined.

Figure 3 is a bottom plan view of the car showing the bolster yoke construction and its relation to the bottom of the car.

2

Figure 4 is a longitudinal section through the bolster, yoke and bottom of the car, taken along the line 4—4 in Figure 3.

Figure 5 is an end view of the bolster yoke construction to show its relation to the bottom of the car, the section being taken along the line 5—5 of Figure 3.

Figure 6 is an end view of the bolster yoke, and bottom of the car taken in section to show the relation of the parts, the section being taken along the line 6—6 of Figure 3.

Figure 7 is a plan view of the floor of the car at one end thereof to illustrate the details of the arrangements of joists in relation to the under carriage.

Figure 8 is a section through the floor of the car taken along the line 8—8 of Figure 7.

Figure 9 is a section through the floor of the car taken along line 9—9 of Figure 7.

Figure 10 is a view in section through the floor of the car similar to that shown in Figure 9.

Figure 11 is an enlarged detail view of a joint formed by the end wall of the car and the bottom thereof.

Figure 12 is an enlarged detail view showing the connection between an end wall and a side wall of a car.

Figure 14 is a section taken through the bolster plate and channel support taken along the line 14—14 in Figure 13.

Figure 15 is a section taken through the bolster plate and channel support to show the relationship thereof to the floor of the car, the section being taken along the line 15—15 of Figure 14.

Figure 16 is a plan view of the end of the channel support.

Figure 17 is a section through the channel support taken along the line 17—17 of Figure 16.

Figure 18 is a section of the channel support taken along the line 18—18 of Figure 17.

Figure 19 is a section transversely through the car taken to show how the cellular construction of the top, side walls and bottom is inter-related.

Figure 20 is a detail of the top corner formed where the top and side wall are brought together.

Figure 21 is a detailed showing of how the side wall and bottom are brought together with the curved corner element on the outer edge of the car.

Figure 22 is an elevation of the door frame and door construction.

Figure 23 is a section taken along the

line 23—23 of Figure 22 to show the relationship of the top and side elements formed around the door frame.

Figure 24 is a detail of the door sill showing the relationship of the side of the car, sill, door, jamb and the floor joists formed thereunder.

Figure 25 is a horizontal section taken through the side of the car above the door sill to show the relationship of the side walls bottom and door sill.

Figure 26 is a section taken through the side of the car under the door sill to show the relationship of the several joists, filler units and parts of the sill.

Figure 27 is a detail of the door frame showing the nailing strip insert.

Figure 28 is a side elevation of a portion of the nailing strip insert shown in Figure 27.

Figure 29 is a plan view showing in detail an element of the nailing strip used for applying strapping.

Figure 30 is a view taken at line 30—30 of Figure 29 to show the relation of the strapping construction to the side wall of the car.

Figure 31 is a side elevation shown with the outer skin of the car removed to illustrate the interior cellular construction of the door.

Figure 32 is a section through the door taken along the line 32—32 of Figure 31.

Figure 33 is a section taken along the line 33—33 of Figure 31.

Figure 34 is a detail view showing the relationship of the door to the door jamb and the mechanism of forming a tight closure.

Figure 35 is a section through the door frame at line 35—35 of Figure 22 to show the relationship of the door frame work to the side wall of the car.

Figure 36 is a section through the door sill of the car showing the relationship of the finished floor line to the door sill and the steel plate.

Figure 37 is a section through the door frame illustrating the relationship of the roof of the car to the curved longitudinal corner element and the top of the door frame.

Figure 38 is a section through the end wall of the car along the center line of the bottom showing the relationship of the draft sill to the bolster yoke.

Figure 39 is a section taken along the line 39—39 of Figure 38.

Figure 40 is another showing of the draft sill taken along the line 40—40 of Figure 38 to illustrate the forward face of the steel shock absorber plate of the draft sill.

Figure 41 is a section along the line 41—41 to show the details of construction at that point in the yoke.

Figure 42 is a bottom plan view of the draft sill showing its relationship to the bolster yoke.

Due to the great reduction in scale compelled by the requirement of showing an object as large as a freight car in the restricted space available, it is to be understood that wherever in the drawings there is shown a laminated construction, each lamination itself is formed of plywood, for example, usually of $\frac{3}{8}$ inch or $\frac{3}{4}$ inch thickness and the grain of the plywood laminations is made to run at about a 45° angle to the axis of the piece being shown.

As indicated, a fundamental object of the invention is to provide a wooden railway car employing a simple cellular laminated construction which will make the car substantially as strong as a steel car employing conventional beam type

construction, but have the superior features attributable to the characteristics of wood, principally that of providing a light car of the same load carrying capacity as a steel car of the same size. Since wood is more easily worked than metal, it also makes the car cheaper to build, easier to clean, maintain and repair.

It has been found that laminated cars built in accordance with the principles set forth in 10 the instant application will be materially lighter than a corresponding steel car. For example, a 40 foot steel refrigerator car will have a tare weight of about 67,000 pounds whereas a 50 foot car of the cellular type construction described herein will have a tare weight of about 54,000 pounds. Where the wooden car is to be used as a refrigerator car, the increased length permits the installation of permanent ice bunkers. Also, in the wooden car the natural insulating 15 qualities of wood enhance the advantages of the construction.

A characteristic of the cellular type construction wherein plywood skins are stressed and fastened across struts is that stresses developed in a car are distributed relatively uniformly throughout the skins forming the shell.

Basically a car made in accordance with the instant invention consists of a shell formed of two or more sheets of plywood adhesively secured to a series of wooden separators arranged in a cellular pattern. The plywood skins take the compression, tension and stresses which develop in the girder construction formed by bonding plywood sheets to the wooden separators and the wooden separators themselves generally take the shear stresses. It should be understood also that complete separation of types of stress is not attainable and that the plywood skins themselves will take some of the shear and the separators 25 will also take tension and compression loads. For example, in the floor of the car where heavy joists are used to separate the layers of plywood in the floor, the lumber rather than taking shear stresses will take both shear and compression forces. Since changes of stress may occur in the 30 end of the plywood floor of the box car, the solid thickness of plywood is built up with the plies running at angles of 45° .

Exhaustive discussion of the development of stresses and strains in a railroad car would be too lengthy for the purpose of the specification. It is to be understood therefore that, in general, the placement of supports and separators throughout the car has been done with a view to efficient transmission of the load in the car through the side walls to the axle of the car and also the efficient distribution of stresses and strains throughout the skin thereof.

A complete understanding of the mechanical structure of the car will be more readily attained by an examination of the drawings together with the accompanying description thereof. For convenience, the various views have been grouped and a new numbering sequence for parts has been adopted for each group with only occasional reference back to a preceding set of figures.

The general views.—Referring first to Figures 1 and 2 the car comprises essentially six panels, a bottom 10, a top 11, sides 12 and 13 and ends 14 and 15, which panels are connectable by means of rounded corner elements at the several longitudinal corners of the box, indicated in Figure 1 as corners 16 and 17, and eight actual corner elements, the three shown being designated as 18, 19 and 20.

The car itself may be visualized as a rectangular box having the six faces held together by longitudinal curved corner elements holding the several faces in their rectilinear position together. At the respective eight corners of the box formed where an end, side and top come together a separate corner element having a double curvature to match the meeting of the side and top, the end and top, side and end is slipped into place.

The car body is hung on bolsters 21 and 22 which in turn provide support for the wheels 23 and 24. The side of the car is equipped with doors of substantially conventional type, for example, doors which may be pulled out of the opening and then slid back along the side of the car substantially parallel thereto being preferred. The door shown in Figure 1 is designated 25.

By making Figure 1 partially a section and partially a phantom view, the cellular construction of the side, end, top and bottom may be seen. The details of the cellular arrangement of spacers and skin in the top, and, sides and bottom will be set forth in the description of subsequent views. For the present it suffices to say that longitudinal and transverse spacers are used in all sides of the car. Thus in the top the transverse spacers in Figure 1 are seen in end section and longitudinal spacers are seen in direct elevation. In the end 15 the skins of that portion of the car appear and a single vertical spacer is seen. In the bottom the laminations comprising the wearing surface appear and directly thereunder the principal transverse joists under the floor are seen in end section and spacers inserted therebetween also appear.

Referring to Figure 2, which is partially a plan view of the top of the car and a section through the walls parallel to the bottom thereof, the cellular construction of the top may be seen. Thus the longitudinal corner element 16 and the corresponding one 16' on the opposite side meet with the end corner element 18. These elements fit within the inner and outer skins of the sides, end and top and are glued in place to hold the car assembled. In the figure the top outer skin is removed showing the transverse and longitudinal spacers 30 and 31. Each of the skins, it is to be understood, is formed of plywood. The edges of the top itself are formed so that the end spacers define substantially the line to which the corner unit reaches in the final assembly.

In Figure 2, the sidewall construction is also shown and it consists of a typical section composed of an outer skin 40, spacers 41, seen in end section, and longitudinal spacers 42, fitting therebetween to form cells, and an inner skin 43. It should be understood that the skins 40 and 43 are of laminated construction and are composed of plywood. The innermost skin itself has a "Masonite" wearing surface which will be shown in detail subsequently.

The formation of the ends is different from the sides and it will be seen that the vertical corner element 44 fits within the inner and outer skins 40 and 43 of the side and is locked in place by means of a spacer 45 which provides gluing surface for the inner face of the corner element. The end is formed of a plurality of vertical supports 46 adhered to each other and to the inner and outer skins 47 and 48.

The framing of the bottom is also indicated in the figure and consists of transverse floor joists 50, spaced from each other by spacers 51 all of which are glued together at their adjoining faces

to provide a supporting surface. The end construction, where the floor joins the end wall of the car, is supported by a plurality of spacers 52 glued to each other to form a firm end for the floor. These end spacers together with spacers 53 and 54 placed among the floor joists at the end of the car provide support for the underlying bolster and yoke.

The doors opening on either side of the car are formed where the side meets a steel frame 55 which includes wood filler 56, which in turn is fastened to the side walls of the car. The details of the construction of the door are set forth in a subsequent portion of the specification.

The bolster yoke.—Since the function of the freight car is to house and haul loads, an important portion of the structure thereof is that of the bolster yoke by means of which the load of the freight is transmitted from the floor of the car to the walls and to the wheels. Also, the draft sill by means of which the car is hooked onto a train and the force of the pull is transmitted to the car is an important portion thereof.

In Figure 3 there is shown a plan view of the bottom of the car to illustrate the location of the draft sill, bolster yoke and structure for receiving the load. Figure 4 is a longitudinal section taken through line 4—4 of Figure 3, showing the relationship of the several parts of the body of the car. Figures 5 and 6 are similarly identifiable as transverse sections at respective planes 5—5 and 6—6 of Figure 3.

Briefly, the bolster yoke consists of a number of plywood laminations 60, forming the basic unit of the structure. In the group of laminations there are formed arcuate and inclined openings 61, 62, 63 and 64 for the two pairs of wheels of a truck which would be mounted on axles supported at these points in the car. It will also be noted that the yoke 60 consists of a series of laminations and it is to be understood each lamination itself is a plywood piece wherein the grains of the several laminae thereof are made to run at 45° angles to the axis of the bolster.

In the figure 65 is a steel plate fastened to the bottom of the car by means of bolts 66 and 67 as shown in Figure 4. The structure of the draft sill by means of which the car is connected to a leading one in a train is shown as consisting of a draft unit 70 which is essentially a steel channel support which at its inner end is recessed into the bolster lamination and held therein by a channel support 71 bolted across the opening of a recess in the bolster. Fastened to the draft unit itself is the steel plate 72, which is backed by a resilient rubber pad 73 placed between the plate and the end of the bolster opening 65. Also formed on the forward sides of the steel plate 72 are the rubber pads 74 and 75. This construction, wherein the steel plate is pushed within forward and rear rubber pads, forms a shock absorber for absorbing the starting and stopping force transmitted thereto by striking plate 70 of the draft sill. The details of construction by means of which this shock absorber and striking plate are held within the opening 68 in the bolster yoke may be seen more readily in Figure 4.

In Figure 4 the floor 49 of the car is seen supported on joists 50 and the laminations of the bolster yoke 60 are seen in section. The steel plate 65 by means of which the bolster yoke is fastened to the bottom of the car is also seen in section.

The forward portion of the drawing shows the

draft sill striking plate 10 fitting into the aperture 68 of the bolster yoke and terminating as steel plate 72 which is backed up by rubber pad 73. Behind the striking plate of the draft sill and adjacent to the steel plate 72 is seen the forward rubber pad 75. The channel support by means of which the draft sill is guided in the aperture in the bolster yoke is seen in section as channel bar 11. Preferably riveted to the bottom of the draft sill unit and seen also in Figure 3 is the steel plate 16 which serves to limit the forward movement of the draft sill under load application. It will be seen that the channel support 11 is also bolted to the floor of the car through laminations in the bolster yoke by means of bolts 17 and 18.

In Figure 5 the section taken along 5-5 in Figure 3 is shown in detail in order to illustrate the relationship of the floor 49 of the car to the bolster yoke and the means by which the load is transmitted thereto. Seen in section are the upper wearing face of the floor and its bottom face with sides 12 and 13, terminating inwardly at the wearing face of the floor where they receive the curved longitudinal bottom corner units 16 which are glued in place by means of filler pieces as indicated and shown in detail in subsequent sections. The floor construction immediately above the bolster, shown in plan in Figure 2, appears in section in Figure 5. Directly over the central mounting for the bolster yoke the floor not only has its transverse joists 50 but has longitudinal filler blocks 53 fitted and glued therein to provide for solid transmission of the load from the floor to the bolster yoke. The yoke 60 itself and the plate 65, which appear in section, are shown in their relationship to the bottom of the car. It is to be understood at this point also that the laminations of the bottom of the car themselves are individually formed of laminated plywood, as are the laminations of the bolster yoke.

In Figure 6 there appears an end elevation of the bolster yoke and its relationship to the bottom of the car as it appears at the plane 6-6 indicated in Figures 2 and 3. Here also the sides of the car 12 and 13 terminate at the finished floor of the car, and inside are fastened to longitudinal curved corners 16 which are held in place by fillers. The recess 65 in the bolster yoke is shown lined with a metal housing 79 of relatively light gauge which serves to unify the formation of the aperture. The laminated bolster yoke construction 60 is seen as being bolted to the floor of the car by means of bolts like 66 and 67. Within the aperture thus defined the rubber pad, steel plate and striking plate of the draft sill are guided in use of the car.

Floor framing details.—In Figures 7, 8, 9, 10, 11 and 12 details of the floor framing, the finishing thereof and the joining thereof to the walls and the corners of the car are shown. Figure 7 is a plan view of a typical end of the car with the wearing surface of the floor removed and the outline of the exterior face of the car dotted in. Thus the car floor remaining consists of a plurality of transverse joists indicated generally as 80, spaced at intervals, for example in a typical embodiment of the car 8", the ends of the joists being held spaced from each other by filler blocks 81 formed of the same weight material as is used for the joists themselves. Typical lumber for this purpose would be nominal 2 x 8, and the filler blocks would constitute pieces of the same material. The joists are thus held in a frame relationship by being glued together at their ends over a large area by the gluing blocks. Spaced be-

tween the joists over the bolster yoke itself in a pattern like that shown, so as to provide rigidity over the bolster yoke, the filler blocks 82 are inserted and glued together in the same fashion as the end fillers. At the end of the car there is arranged a series of end filler blocks 83 across the entire width thereof, corresponding in size and shape to the joists.

In Figure 8 this arrangement of joists and fillers is shown as related to the finished wearing surface 84 of the floor of the car. Similarly, the forward end of the car 85 is seen terminating at the floor and joining the corner element 86 which is glued in place to the bottom face 87 of the floor and held rigidly in place by insertion over the filler blocks 83.

In Figure 9, which is the section taken along the line 9-9 of Figure 7, the relationship of the floor joists to the filler blocks arranged at right angles thereto, is seen, and the joist 90 is seen in plan and the fillers 91 in section. The floor surface itself consists of a plywood surface 92 glued directly to the floor joists and filler strips to which is attached a Masonite wearing surface 93. It is understood that the plywood surface 92 can be a single layer of relatively heavy plywood, or a plurality of layers of lighter wood. Similarly, the plywood bottom skin of the floor forms part of the joint between the cellular floor and the side walls where corner element 95, typical of those used at any corner edge of the car, meets with the side 96 of the car and the bottom thereof. At those points where the corner 95 contacts the inner surfaces of the side 96, it is glued in place. Similarly, at point 97 where the corner 95 meets the bottom skin of the car, it is glued and filler 98 serves as a keying unit to provide firm connection between the entire corner element and the upper skin, as well as the bottom skin of the floor. Thus the corner element is glued to the side and bottom of the car over its entire interior face and only the exposed exterior curved section is not glued thereto.

The details of this glued, keyed joint, may be seen by examination of Figure 10, taken along plane 10-10 of the Figure 7, where the end blocks are identified as 98 in Figures 9 and 10.

In Figure 11 the manner in which the end of the wall of the car is connected to the bottom is shown, thus to relate the parts of the bottom to those shown in Figures 7 and 8. The joists identified generally as 80 in Figure 7 are seen as joist 100 in Figure 11. The series of gluing block identified as 83 in Figure 7 appears as such in Figure 11. The upper skin of the floor shown consisting of a pair of layers of plywood, corresponds to the skin 92 shown in Figure 9, which is topped with a wearing surface 93 of "Masonite." Similarly, the bottom skin of the floor is formed of a plurality of layers of plywood 101, 102 and 103, the inner one 101 being terminated short of the forward edge of the floor and being of a thickness to match the thickness of the forward curved corner element 104. The forward end of the car has its outer skin 105, like the other skins thereof, formed of a plurality of layers of plywood adhered to inner framing members 106, which in turn carry an inner skin 107 which is made of a plurality of layers of plywood topped with a wearing surface 108 of "Masonite." The gluing area between the forward curved bottom corner element 104 and the outer skin of the end of the car is provided at 109, the inner skin of the car being brought down within the curve of the corner thereof and a correspondingly shaped

keying element is inserted in place to provide a gluing area at 110 for the inner surface of the inner skin of the car. The gluing area of the bottom filler blocks 83 is obtained along the bottom face 111 of the inner skin of the car and the inner face 112 of the curved corner member 104. It will be seen that the corner member 104 is laminated of a plurality of layers of plywood, which equal the thickness of the inner skin of the bottom of the car 101. The block 83 thus serves to furnish gluing area for the bottom of the car 92, the adjacent forward joist 100, the bottom skin of the car 101, the curved corner element 104 and the inner skin of the forward end of the car 111.

In similar fashion, Figure 12 is a section showing details of the connection between the end of the car and a side wall thereof. In this figure those portions of the end corresponding to those in Figure 11 are numbered accordingly. The vertical curved corner element 120 passes from the end of the car between the inner skin 121 and the outer skin 122 of the side wall of the car. The gluing area is obtained by contact of the curved member 120 at 123 and filler block 124 is provided to give an inner gluing surface to the curved corner member, the extended edge of the end 111 of the inner skin of the car, and the inner surface of the side wall 121. Some tolerance for size is provided by the gap 125. It is to be understood that the wood filler 124 will have its grain running at right angles to the side wall framing members 126, which are shown in section.

Additional details of bolster yoke.—In Figures 13, 14, 15, 16, 17 and 18, details of construction and suspension of the bolster yoke are shown. Thus the relationship between Figures 13 and 14 is that of plan and elevation of the bolster yoke. In Figure 14, which is an end elevation of the bolster yoke, showing parts of the floor construction in section, it will appear that the floor is shown consisting of the topmost wearing surface of "Masonite" 130, a pair of plywood layers 131 and 132, which are mounted on a transverse joist 133, that transverse joist contacting a plurality of spacers 134. The bottom skin of the floor similarly is composed of a pair of layers of plywood 135 and 136. The yoke itself consists of a plurality of layers of plywood, generally indicated as 137 and it is to be understood that in this laminar construction each individual layer is formed of plywood and preferably the grain of the individual laminations of the plywood is set to run at an angle of 45° to the axis of the bolster. The layers are glued one to the other and the bottom face of the bolster is finished off with a steel plate 138, the entire assembly being hung from the floor of the car by means of bolts 139 and 140. The bolster yoke has a reinforcing head 141 fastened to the bottom reinforcing plate thereof, the entire assembly being fastened to the bottom of the car by means of bolts 140. Steel-lined recesses are provided for the heads of the several bolts.

The reinforcing head for the bolster yoke provides a truck support in the form of a circular bearing head 142 in which is centered an opening 143 to receive a coupling pin for connecting the wheel truck to the bolster yoke. Seen in section in Figure 14 it will appear that the recess 143 is steel-lined for the reception of the pin coupling the truck thereto.

In Figure 15, which is a section taken along the plane 15—15 of Figure 14, the relationship of the

several parts of the yoke to the floor may be seen. Therein are identified the several laminations forming the upper skin of the floor, the plurality of joists indicated generally as 133, and filters 134, as well as the several bolts holding the bolster yoke construction on the bottom of the car.

Figures 16, 17 and 18 are detailed views and sections of the channel support and the means employed for fastening the channel to the bolster. Thus in Figure 16, 150 is the channel and 151, 152 and 153 are the bolt supports fastening it to the floor of the car. Details thereof are shown in Figures 17 and 18.

Details of a typical cross-section of the car.—

Figures 19, 20 and 21 constitute a typical cross-section transversely through the car to illustrate the laminated cellular construction thereof and Figures 20 and 21 are enlarged detailed showings, respectively, of typical corners at the top and bottom of the car.

Thus, in the figure it appears that the roof and side walls of the car are substantially of the same kind of cellular construction in that the roof will have an outer skin 160, transverse supports 161, longitudinal spacers 162 and an inner skin 163. It is to be understood that the outer or inner skin may be made up of one or more layers of plywood, which of course themselves are laminated. Similarly, a side wall consists of an outer skin 164, vertical supports 165, longitudinal spacers 166 and an inner skin 167. The floor is composed of an inner wearing surface 168, plywood bearing surface 169, transverse supports 170 and an under skin 171.

Referring to Figure 20 showing the details of a connection of the top to a side wall, it will appear that the outer skin 160, consisting of its several layers of plywood, is formed with a longitudinal support 162 set in from the edge thereof, and that the inner skin 163 defines therewith an opening for the reception of the curved corner element 172. The bearing surface 173 formed by the over-lapping of the outer skin 160 onto the longitudinal corner element 172 provides a gluing area 173 and a similar gluing area 174 is formed between the corner element and filler 175, with additional gluing area 176 between the filler and inner skin 163 of the car. In similar fashion, the over-lapping of the outer skin 164, one with a flat portion of the curved corner element, provides gluing area 177 and the insertion of a filler 178 between the inner skin 167 and the corner element provides additional gluing areas 179 and 180.

In corresponding style a maximum of gluing area is provided between the lower corner element 190 and the side wall and floor. Thus the outer skin 164 forms gluing area 191 with a flat portion of the corner element and the filler 192 provides gluing area 193 between it and the corner element; gluing area 194 is formed between the filler and the inner skin of the side wall. For joining the side wall to the floor, the wearing surface of the floor is recessed slightly to form the corner 195 matching the termination of the inner side wall of the car. Gluing area between the corner element and filler 196 is obtained in ample amount by fitting it to the curvature of the corner element; the bottom or outer skin of the bottom 171 forms gluing area 198, with the corner element corresponding to area 197 formed on the inside surface thereof.

It will be apparent from this detailed showing of the formation of the longitudinal corners at top or bottom of the car that the objective in

holding the cellular tops and side walls together is to provide a large gluing surface between the corner element and the adjacent side of the car so as to develop the needed strength. That is, rather than concentrate stresses at a point such as is done by the use of bolted joints, the distribution of stresses is accomplished by providing large gluing areas at the joints of the structure. Also this unitary construction by which the floor framing including joists and end fillers (Figure 7) is carried through to join the floor to the side walls aids materially in distributing load from the floor to the walls.

The door frame and sill.—In Figures 22 and 23 the general arrangement of door frame for the car and the joining thereto of the roof, floor and side elements is shown. In Figure 22, the left hand side of the drawing is an exterior elevation of the door frame and the right hand portion is an interior elevation thereof.

Thus, 200 represents the outside side wall of the car and 201 the longitudinal upper curved corner element joining the side wall to the roof 202. In the interior elevation the side wall in relation to the roof 202 is shown so that the arrangement of the steel door frame 203 around the door opening can be seen. Thus the side wall 200 and longitudinal corner element 201 meet in a joint like that shown in Figure 20, and the opening left for the door of the car is outlined by steel framework 203 which laps over the side wall 200 on the outside and laps on to the inner skin of the car to a lesser degree on the inside. This appears more clearly in the right-hand section of Figure 23, where the inside portion of the door frame is identified as 204, and is aligned with the upper edge 205 of the inner skin of the car. The exterior door frame terminates at the bottom edge of the side wall 200 where it meets the steel door sill 206, which laps over the upper and bottom skins of the floor construction and is bolted in place with bolts such as 207.

The interior door frame shown aligned with the exterior elevation is substantially as wide as the exterior frame in the vertical portions thereof and slightly reduced in the horizontal upper portion. The vertical portion 210 of the door frame has a channel 211 formed therein, which channel furnishes a slot for a wooden insert to provide a nailing strip for the packing of goods in the car. The door frame is held in place by means of counter-sunk through-bolts, such as 212, which are spaced at intervals around the frame. As shown in the section comprising Figure 23, the steel door frame is made of a thickness which will place its inner surface flush with the inner skin of the wall 205. Similarly, the door sill 206 is made of a thickness corresponding to the wearing layer 168 of the floor of the car, so that a flush surface is presented directly over the interior of the car and the sill to the exterior.

Details found at the door sill are shown in Figures 24, 25 and 26, and further details of nailing strips and strapping connections around the door frame itself are shown in Figures 28, 29 and 30.

Referring to Figure 24, which is an elevation of the door sill and portion of the door frame meeting it, the steel door frame 203 will be seen where it meets the steel sill 206 held in place by bolts 207. The relationship of the side skin 200 to the steel jamb and the floor joist and filler strips is seen in the figure where the side 200 terminates at the ends of the floor joists in a rounded corner element in the fashion shown in Figure 21. In as-

much as loading of a freight car frequently calls for rough use of the structure around the opening of the door, the steel sill 206 is provided to extend from one extremity of the door frame to the other over the end of the floor construction. Details of this feature are better shown in Figure 25 which is a plan view of the door sill wherein 200 represents the outer skin of the car terminating in a joint connecting it to the steel door frame. Thus 220 is a vertical support in the side wall of the car which is glued to the wooden filler 221 which in turn is glued to the inner and outer skins of the car itself. Filler 221 is covered by the steel door frame 203 which is bolted thereto at intervals in the manner illustrated. The form of the door sill 206 and its connection to the floor of the car are apparent from the figure. The steel door frame 203, shown in cross-section, is provided with the channel structure 211 for the reception of nailing strip as may be needed from the inside of the car.

In Figure 26 the relationship of the floor joists of the car, the filler blocks and the points of connection of the door sill thereto are shown in their relationship to the side wall.

Figures 27, 28, 29 and 30 detail one arrangement of nailing strip and strapping bars around the door frame. Thus in Figure 27 the steel door frame 203 with its channel 211 is shown, the channel being filled with nailing strip 212 which is interrupted at intervals by strapping bars 213, 214 and 215. Each of the strapping bars, as indicated in Figure 28, consists of a generally U-shaped member 216, which is bolted in place to the base of the channel 211, by means of bolt 217 and has joined thereto an inverted U 218 which is of lesser width than the width of the channel so that steel straps may be placed under the unit 218 and crimped in place. The arrangement is shown in detail in Figures 29 and 30.

Door details.—In Figures 31, 32 and 33 and 34, details of the car door construction and manner in which it fits the door jamb are shown. Figure 31 is a plan view showing the interior framing of the door with vertical supports and lateral spacers or fillers, the plywood skins being mounted thereon. The steel edge or trim for the door is identified generally as 225.

In Figure 32, which is a horizontal section taken along the line 32—32 in Figure 1, it will appear that the door consists of the several vertical supports, the outer and inner skins, and the edge is reinforced with the metal frame consisting of a pair of angle irons, one a Z-shaped iron 226, and the other an L iron 227, which are fitted on to the door in overlapping relation to be flush with the inside and outside surfaces thereof and to furnish an outwardly extending tongue around the door edge.

In Figure 33 the door when closed is shown in its relation to the top of the door frame and the bottom door sill and it will appear that the outwardly extending tongue overlaps the door frame opening.

In Figure 34, an enlarged detailed showing of the construction of the door edges, it appears that the door frame edge consists of the irons 226 and 227 held in place by bolts 228 and that the outwardly extending side of the iron 226 forms a frame overlapping the edge of the door opening. Carried on the inner face of the said extending edge of the door is a spring compression gasket 229 which is riveted to the leg of the Z bar 226 by means of rivet 230. Gasket 229 is of a spring steel strap material and in its relaxed position is

circular in form and has approximately the outline shown as 231 in Figure 34. Upon closing of the door the strap is compressed to the form shown in full lines.

In Figures 35, 36 and 37 some additional details of the exterior door frame section are shown. Thus Figure 35, which may be considered a section along the line 35—35 in Figure 22, shows outside skin 200 of the car formed of a plurality of layers of plywood and the inside skin 205 likewise formed of a plurality of layers of plywood as they are joined to the door frame. Vertical support 230 appears in section to form a recess for the insertion of the laminated plywood door frame filler 231' which is mounted within the steel door frame trim 210. Bolt 212 is typical of those used to hold the door frame in place. It will be seen also that on the inside face a channel is provided for the nailing strip 25.

This construction provides ample gluing area around the door frame at the surfaces 232 and 233.

Figure 37 may be considered a section taken along the line corresponding to 37—37 of Figure 22 and shows in detail the relationship of the door frame 210 to the longitudinal corner element 201 and the top of the car 202.

It will be seen in this figure that the top skin 202 of the car is composed of a plurality of layers of plywood and extends past a longitudinal support 240 which has mounted on the underside thereof an inner skin 241 composed of a plurality of layers of plywood. Filler block 242 between the inner skin and the longitudinal corner element 201 provides ample gluing area along the surface 243 and, in turn, longitudinal corner element 201 and top skin 202 provide substantial gluing area along the surface 244.

The corresponding arrangement of parts on the top of the door frame shows the longitudinal corner element meeting with the built-up plywood door frame liner 250 to define a substantial gluing area 251 and 252 on the opposite faces thereof.

Figure 36, which may be considered a section taken along the line 36—36 of Figure 22, shows the door sill 206 consisting of a straight steel channel bar held in place along the top and bottom skins of the floor by means of the bolts 207. It will be noted that the floor of the car consists of its wearing surface which is made flush with the door sill and a plurality of skins of plywood laminated thereunder. A similar construction of the bottom edge of the door frame includes a filler block 269 adhered to the end plate 261 of the floor. This latter is held in squared relation with the base of the door sill by bolts 262.

Draft sill details.—Figures 33, 39, 40, 41 and 42 give details of the draft sill construction and the manner in which it is connected to the bolster yoke. In this group, Figures 38 and 42 have the relation of being a vertical section and plan view, respectively. Thus 300 represents the floor of the car which is framed in from the bolster yoke 301 which is composed of a large number of plywood laminations and along the bottom thereof has the steel plate 302 carrying the center pin opening 303 for orientation over the truck of the car. The channel support 304 is held in place across the forward edge of the bolster yoke by means of the bolts 305 and with steel plate 306 defines a metal lined opening in which draft sill 307 is adapted to slide. The forward portion of the floor immediately above the draft sill carries a metal liner 309 to define the guide for the draft sill 307. The sill itself is made up of an I beam

which by means of pivot lever 310 is fastened to a second pivot point 311 on the forward end of the car. This mechanism forms a satisfactory striking plate for limiting the movement of the draft sill. Within the bolster yoke itself the metal plate 312 on the draft sill is incorporated into a shock absorber mechanism described in connection with Figures 3, 4, 5 and 6 wherein the rubber pads 313 and 314 adequately absorb the shocks developed in the use of the car.

The corresponding parts are shown in the bottom plan view of the draft sill in Figure 42 wherein common identifying numerals render additional detailed explanation unnecessary. Channel bar 304 is seen held in place by a pair of bolts at either end. The draft sill 307 is seen to fall short of reaching the extreme inner end of its opening in the bolster yoke and the rubber pads forming the shock absorber in connection with steel plate may also be seen in place in the bolster yoke.

Similarly, Figure 40, which is a section taken transversely across Figure 38 at the face of the steel striking plate illustrates that the shock absorption is accomplished by providing a relatively large area of plate to reduce the compressive force of an impact to a relatively small force per unit area. It will also be seen that the impact thus transmitted through the steel plate is transferred against the metal liner 320 of the shock absorber opening which in turn transmits the force to the ends of the grains of the laminations of plywood in the bolster yoke.

Figure 41, which shows a section taken across Figure 38 at line 41—41, illustrates the relationship of the draft sill to the bolster yoke, the channel bar and the opening within which the draft sill is permitted a limited amount of longitudinal movement of the car.

In the foregoing paragraphs frequent reference has been made to adhesively joining the several parts of the car. It is to be understood that glues of appropriate strengths will be used and, for the purpose, the new synthetic resin-base glues would be preferred. Generally, waterproof glues would be preferred.

Though the invention has been described with only a limited reference to specific embodiments of the elements thereof, it is to be understood that variations in features of construction of the car may be made without departing from the spirit or scope of the invention.

What is claimed is:

1. In a vehicle comprising a housing of laminated cellular construction having a unitary laminated cellular panel forming the floor thereof, the improvement comprising forming said floor over transversely extending supports, a plurality of filler units joining the ends thereof and a pair of bolsters extending transversely of the housing at either end thereof and fitted to said panel from the bottom, said bolsters being formed of a plurality of plywood laminations, the floor immediately thereover being characterized by the inclusion of filler blocks in an extended area corresponding substantially to that of the bolster.

2. In a car construction in accordance with claim 1, the improvement comprising the arrangement of end supports between the said joists, the supports being filler blocks spacing said joists and forming a substantial gluing area therebetween, thereby to define a complete heavy support around the perimeter of the car, the filler blocks at the ends being arranged with their grain running longitudinally of the car and a pattern

of filler blocks corresponding to the bolster yoke included between the joists in the area directly above the bolster yoke under the car.

3. In a vehicle body comprising a shell of laminated cellular construction having unitary laminated cellular panels forming the floor and walls thereof, an improved joint comprising a pair of laminated panels having inner and outer skins arranged in right angle relation to each other, the inner skins coming together to form a right angle joint, a curved corner member for interconnecting said panels, comprising a plurality of laminated sheets of transversely curved plywood adhered to the inner faces of the outer skins of said two cellular panels and filler blocks inserted between the said curved corner member and the inner surfaces of said two cellular members.

4. In the combination of claim 3, the joint being characterized by being formed entirely of plywood elements adhesively joined to each other.

5. In a railway car comprising a shell of laminated cellular plywood construction characterized by having unitary laminated floor, wall, and roof panels and unitary corner members interconnecting said panels to form a monocoque housing, the improvement comprising forming the floor thereof with transverse, substantially uniformly spaced joists and including between the ends of said joists a plurality of relatively short filler units, said filler units being adhered to each other and to adjacent joists, and adhering thereto inner and outer skins formed of a plurality of plywood laminations.

6. In a car in accordance with claim 5, an improved end wall construction comprising a plurality of spaced vertical supports and inner and outer skins adhered thereto, the inner skin of said end wall being longer than its outer skin.

7. In a car in accordance with claim 5, a bottom end joint wherein an end wall meets the bottom thereof, characterized by having the inner skin of the bottom and end wall form a right angle corner in the car, part of the end wall skin extending substantially down to the outer skin of the bottom of the car, and a longitudinal corner element adhered to the outer skin of the end wall and the bottom and filler units fitted between said longitudinal corner unit and the respective sections of the end and bottom.

8. In a car in accordance with claim 5, an improved bottom and end joint characterized by having the inner skin of the bottom and end wall form a right angle joint, part of the lamination of the end wall being extended down to the outer skin of the bottom, a longitudinal corner unit being fitted between the outer skin of the end wall and the bottom, and filler blocks between said longitudinal corner units and the corresponding sections of the end wall and bottom, the filler blocks being arranged with their grain running longitudinally of the car between the inner skin of the end wall and the first transverse joist of the floor, thereby to form a solid beam across the end of the car.

9. In a railway car comprising a shell of laminated cellular plywood construction characterized by having unitary laminated floor, wall, and roof panels and unitary corner members interconnecting said panels to form a monocoque housing, the improvement in draft sill and bolster yoke construction comprising, arranging filler blocks in the laminated floor construction in a load bearing pattern at each end of the car over the location of a truck for mounting the

wheels, a bolster yoke fastened to the bottom of the car thereunder comprising a plurality of layers of plywood and a channel formed in said bolster yoke, said channel being metal lined and receiving therein a draft sill, a shock absorber plate on said sill and integrally joined thereto, said shock absorber plate bearing against resilient shock absorber pads in said channel, and a pivot link support holding the forward end of said draft sill in horizontal draft relationship to the front end of said car.

10. A vehicle body comprising a shell of wood laminated cellular construction, consisting of unitary laminated floor, wall and roof panels, and unitary corner members interconnecting said panels to form a monocoque housing, the end panels thereof being formed of a plurality of vertical supports placed adjacent to each other and adhered to each other and having inner and outer skins adhered thereto.

11. The combination in accordance with claim 10 in which the floor panels are formed with transverse joists and have their ends spaced from each other by filler blocks adhered thereto.

12. In the combination of claim 10, the corner members consisting of a plurality of spaced plywood sheets and separator members fastened therebetween.

13. In the combination of claim 10, a pair of bolster yokes forming the under-carriage for the car, and steel draft sills attached thereto.

14. In the combination of claim 10, a pair of bolster yokes forming the under-carriage for the car, each consisting of a plurality of plywood laminations.

15. A vehicle body comprising a shell of laminated cellular construction having a unitary laminated cellular panel forming the floor thereof, said panel being formed in part of a plurality of transversely arranged joists, a pair of laminated bolsters extending transversely of the shell near each end thereof, and draft sills fitted to said floor panel from the bottom and extending outwardly from said bolsters at each end of the vehicle, and means for securing the outer end of each draft sill to the end of said shell.

16. A structural joint comprising a pair of laminated cellular members brought together in substantially right angle relation and held in such relation by a longitudinal curved corner member meeting at least one face of each of said cellular members, said longitudinal corner member itself being a laminated plywood element.

17. A joint in accordance with claim 16 in which the longitudinal corner element meets the inner faces of each of said cellular members and is held adhered thereto with filler blocks placed therebetween and the second face of each of said members.

18. A structural joint comprising a pair of wall members brought together in substantially right angle relation, one of said members being a laminated cellular structure formed with inner and outer skins and interior spacers and supports, the other of said members being a solid one formed of inner and outer skins and a plurality of adjacently placed internal supporting members.

19. In a structural joint in accordance with claim 18, a longitudinal corner element holding said members in substantially right angle relation, said element being adhered to a face of each of said members.

20. A joint in accordance with claim 19 in which the said longitudinal corner element is a laminated structure formed of a plurality of

sheets of plywood and is keyed in place by a plurality of filler blocks adhesively joined thereto and to a parallel face of the joint.

21. A structural joint comprising a pair of panels brought together in right angle relationship, one of said panels being a solid member consisting of inner and outer skins and a plurality of supports adhesively joined to each other therebetween, the second of said panels forming the joint comprising a plurality of transverse supports, inner and outer skins adhesively joined thereto and, adjacent to said first panel, a plurality of filler blocks adhesively joined to each other and to the inner skin of said first panel and a longitudinal corner element holding said two panels in right angle relationship.

22. In a vehicle body comprising a shell of laminated cellular plywood construction characterized by having unitary laminated floor, wall and roof panels and unitary corner members interconnecting said panels to form a monocoque housing, the improvement in the floor panel comprising a plurality of spaced reinforcing timbers extending transversely of the panel, a plurality of filler blocks filling the spaces between the ends of said timbers and adhesively bound together and to said timbers to form a continuous reinforced periphery for said panel, and plywood skins adhesively bound to the opposite faces of said timbers, filler blocks and corner members.

23. In the combination of claim 22, a plurality of filler blocks adhesively incorporated in and directed longitudinally of the floor panel and concentrated between said transverse timbers in the area of the floor panel near each end of the car to form a reinforced area for bolster yokes.

24. In the combination of claim 23, a bolster yoke comprising a plurality of superposed layers of plywood adhesively bound together and attached to the undersurface of the floor panel in the area of concentration of said filler blocks.

25. In the combination of claim 23, a third set of filler blocks interposed between said skins at the ends of said floor panel and adhesively bound thereto and to each other in a continuous array.

26. In the combination of claim 22, said wall and roof panels each comprising a pair of par-

allel plywood skins adhesively united by a network of separators and said unitary corner members each comprising a plurality of superposed adhesively bound layers of plywood of curved cross section adhesively connecting the adjacent edges of said panels in pairs to form a monocoque shell.

27. A vehicle body comprising a monocoque shell composed of laminated plywood roof, floor, side wall and end wall panels and curved corner members interconnecting said panels at the proximal edges to form a self-sustaining and load-sustaining housing, in combination with a pair of bolster yokes comprising a plurality of superposed adhesively bound layers of plywood attached to the under surface of the floor panel at the respective ends of said housing.

28. In the combination of claim 27, king pin plates attached to the exposed faces of said bolster yokes.

29. In the combination of claim 27, draft sills recessed into the outer ends of said bolster yokes and resilient impact members longitudinally aligned with said draft sills and lying in the draft sill recesses.

30. In the combination of claim 29, a linkage system for pivotally connecting the free ends of the draft sills to the adjacent end walls of the housing.

BERTRAND GOLDBERG.
